Primary Examiner—Robin V. Webster*Assistant Examiner*—Karen E Kearney(74) *Attorney, Agent, or Firm*—Arent Fox LLC(57) **CLAIM**

The ornamental design for a candy bar, as shown and described.

DESCRIPTION

FIG. 1: is a front, left perspective view of the candy bar showing our new design;

FIG. 2: is a top view of the design shown in FIG. 1;

FIG. 3: is a bottom view of the design shown in FIG. 1;

FIG. 4: is a front view of the design shown in FIG. 1; wherein the rear view is a mirror image thereof;

FIG. 5: is a right side view of the design shown in FIG. 1;

FIG. 6: is a left side view of the design shown in FIG. 1;

FIG. 7 is a second embodiment of a front, left perspective view of the candy bar showing our new design; and,

FIG. 8 is a top view of the design shown in FIG. 7.

The broken lines showing the indicia in FIGS. 7 and 8 are for the purpose of illustrating environmental structure and form no part of the claimed design.
